ATTORNEY

UNITED STATES PATENT OFFICE

EDWARD K. JANNEY, OF BUENA VISTA, VIRGINIA

SAFETY HASP

Application filed September 27, 1929. Serial No. 395,620.

This invention relates to hardware and more particularly to hasps such as are used in connection with staples for locking doors and the like.

5 A primary object of the invention is to so construct a hasp of this character that when not in use, that is when the door is unlocked, it will be folded and held to prevent the loose member from catching and scratching the 10 door, and from engaging and tearing people's clothing.

Another object of the invention is to provide a hasp, the foldable members of which are provided with interengaging elements 15 which while effectively holding them in inoperative position may be readily opened when desired.

Another object of the invention is to construct a hasp with foldable members provided 20 with interengaging elements so that when packing the devices for shipment the cooperating staple member may be located between these foldable elements and held to avoid danger of loss, and to permit a greater number 25 to be packed in a single bundle.

In carrying out these objects, the invention is susceptible of a wide range of modification without departing from the spirit or sacrificing any of the advantages of the claimed 30 invention; there being shown in the drawings for illustrative purposes a preferred and practical form, in which:

Figure 1 represents a perspective view of a hasp constructed in accordance with this 35 invention with the members in open position;

Fig. 2 is a side elevation with the members shown closed and held; and

Fig. 3 is a view similar to Fig. 2 with the 40 staple member shown located between the folded hasp members ready for shipment;

Fig. 4 is an enlarged detail view showing the interlocking engagement between the members of the hasp.

In the embodiment illustrated the hasp constituting this invention is composed of the usual parts 1 and 10 which are hingedly connected together as shown at 11. The member 1 is designed for being fixedly secured to a door, screwholes 2 being provided for that purpose, while the member 10 is designed to

be engaged with a staple and has a slot 12 for such engagement. The usual lip 13 is provided at the free end of the member 10 to facilitate the opening and closing of the member. At the inner end of the opening 12 is 55 provided a laterally and rearwardly extending spring tongue 14 which is designed for interlocking yielding engagement with a similar tongue 3 formed on the member 1 in a position to be so engaged when the member 10 is in folded inoperative position as shown clearly in Figs. 2 and 3. The member 1 has an opening 4 therein with the tongue 3 located at the outer end thereof and slightly curved toward the hinge connection of the member 60 and when the two parts are folded these tongues will yieldably engage and securely hold the members together, yet when it is desired to open the member 10 it may be freely separated from the other by slightly pulling 65 the same.

The staple 5 which is used in connection with the hasp is usually mounted on a base plate 6 as shown clearly in Fig. 3 and when the hasp and staple are packed for shipping 70 they may be arranged as shown in Fig. 3 with the staple passed through the opening 12 and the member 10 held engaged with the member 1 thereby securely locking the parts together 75 and avoiding all possibility of them becoming separated and lost.

From the above description it will be obvious that a hasp constructed as shown and described will hold the members 1 and 10 securely yet yieldably locked in folded position and by arranging the elements 3 and 14 near the hinged ends of the parts greater leverage is afforded rendering it easy to open the members.

Without further description it is thought 85 that the features and advantages of the invention will be readily apparent to those skilled in the art, and it will, of course, be understood that changes in the form, proportion and minor details of construction 90 may be resorted to, without departing from the spirit of the invention or its scope as claimed.

I claim:

1. A hasp composed of hingedly connected 100

members provided on their inner faces with interlocking elements to hold said members yieldably in folded inoperative position.

2. A hasp composed of hingedly connected members having spring tongues for interlocking engagement to hold them in yieldable connection.

3. A hasp composed of hingedly connected members having spring tongues for interlocking engagement to hold them in yieldable connection, said tongues being located adjacent the connection of said members to afford greater leverage and to facilitate opening of the members.
